HAND TROWEL

Fred W. Tims, Jr., Stratford, Conn., assignor to The Camson Manufacturing Company, West Haven, Conn., a corporation of Connecticut

Filed Sept. 4, 1968, Ser. No. 13,399

Term of patent 14 years

Int. Cl. D8—02

U.S. Cl. D8—45

FIG. 1 is a perspective view of a hand trowel showing my new design;

FIG. 2 is a side elevation thereof;

FIG. 3 is a top plan view thereof;

FIG. 4 is an end elevation thereof; and

FIG. 5 is a partial bottom plan view.

The dot-and-dash lines in FIGS. 1, 3 and 5 are understood to be representative of the continued appearance of the solid lines of which they are a continuation.

I claim:

The ornamental design for a hand trowel, substantially as shown and described.
